RECOIL PAD FOR FIREARMS

Frank A. Pachmayr, Culver City, Calif.

Application January 23, 1950, Serial No. 7,415

Term of patent 14 years

(Cl. D30—1)

To all whom it may concern:

Be it known that I, Frank A. Pachmayr, a citizen of the United States, residing at Culver City, in the county of Los Angeles and State of California, have invented a new, original, and ornamental Design for a Recoil Pad for Firearms, of which the following is a specification, reference being had to the accompanying drawing, forming part thereof, in which:

Fig. 1 is a side elevational view of a recoil pad for firearms, showing my new design;

Fig. 2 is a top plan view;

Fig. 3 is a fragmentary, partly sectional view taken on the broken line 3—3 of Fig. 2; and

Fig. 4 is a fragmentary plan view in the direction of the arrow 4 of Fig. 3.

The side of the recoil pad opposite to that shown in Fig. 1 is of the same configuration as the side shown in Fig. 1 so that the same appearance is presented by both sides of the pad.

I claim:

The ornamental design for a recoil pad for firearms, substantially as shown and described.

FRANK A. PACHMAYR.
